DESIGN FOR A BUCKLE

Edwin S. Mix, Rochester, N. Y., assignor to
Hickok Manufacturing Company, Inc., Rochester, N. Y., a corporation of New York

Application July 11, 1936, Serial No. 63,809

Term of patent 3½ years

To all whom it may concern:

Be it known that I, Edwin S. Mix, a citizen of the United States, residing at Rochester, in the county of Monroe and State of New York, have invented a new, original, and ornamental Design for Buckles, of which the following is a specification, reference being had to the accompanying drawing, forming part thereof.

In the drawing:

Fig. 1 is a front perspective view of a buckle showing my new design;

Fig. 2 is a longitudinal sectional view on line 2—2 of Fig. 1; and

Fig. 3 is a transverse sectional view on line 3—3 of Fig. 1.

The dominant feature of the design resides in the buckle having the front thereof provided with a group of three side by side ornamentally framed character bearing panels two of which are arranged in horizontal alinement and the other panel being of greater length than the other two panels and extending beyond the upper and lower ends of said other two panels, the initial shown being merely illustrative.

I claim:

The ornamental design for a buckle, as shown.

EDWIN S. MIX.
